United States Patent Office.

ALMON T. MORRIS, OF NEVADA, OHIO.

Design No. 4,262, dated July 26, 1870.

DESIGN FOR A CORN-HUSKER.

The Schedule referred to in these Letters Patent and making part of the same.

To all whom it may concern:

Be it known that I, ALMON T. MORRIS, of Nevada, Wyandot county, Ohio, have invented and produced a new and original Design for a Corn-Husker; and that the following is a full, clear, and exact specification thereof.

Description of Accompanying Drawing.

Figure 1 is a side view of my design for corn-husker.
Figure 2 is a plan of the same.

Figure 3 is a cross-section of the ring in said husker.
Figure 4 is a perspective view of the same.

General Description.

The nature of my design is to give such a form to a corn-husker as to adapt it to the upper ends of the first and second fingers of the right hand, and to cause it to readily enter the husk and act as a means of tearing open the same, without throwing too severe strains on the fingers on which it is worn.

The husker consists of a close ring, A, having the

open bend C cast on its right-hand side, and the tusk B on its left-hand side.

The ring A is made with a hole, which is made larger at the end b than at the end a, as shown in fig. 3, in order to give room for working the ends of the fingers, to avoid cramping them.

The tusk B is made with its lower face nearly at right angles with the circumference of the ring A, and has a sharp straight cutting-edge, c, the upper face being carried up at a considerable angle with the lower face, as shown, to give the proper strength to the tusk.

The cross-section of the husker, at any part, is of a rectangular form.

Claim.

What I claim as my invention is—

The design for a corn-husker herein described and represented.

ALMON T. MORRIS.
